UNITED STATES PATENT OFFICE.

EDWARD C. KELONGE, OF AURORA, ILLINOIS.

WALLED SAFE.

937,215.

Specification of Letters Patent. Patented Oct. 19, 1909.

Application filed January 4, 1909. Serial No. 470,805.

To all whom it may concern:

Be it known that I, EDWARD C. KELONGE, a citizen of the United States, residing at Aurora, in the county of Kane and State of Illinois, have invented certain new and useful Improvements in Walled Safes, of which the following is a specification.

The object of this invention is to secure a safe within the wall of a partition by means which are operated from within the safe.

The further object of this invention is to form a fluted air space around the edges, back and ends of the safe.

15 The further object of this invention is to cover the fluted air space with concrete.

In the accompanying drawings, Figure 1 is a vertical section through the safe and through the partition supporting it. Fig. 2 20 is a perspective view of the safe in which the supplemental back is separated from the safe proper.

The safe proper comprises the front 1 to which the door 2 is hinged in the usual manner, the sides 3, ends 4 and back 5 suitably connected are formed of a single piece if desired. The interior arrangement may be made to suit the purchaser. The back 5 is formed with four openings 6. The supplemental back 7 has an edge flange 8. Screws pass through the openings 6 in the back 5 of the safe proper into the bosses 10 extending from the inside of the supplemental back. Around the sides 3, ends 4 and back 5 of the 35 safe proper between the front 1 and the supplemental back 7 is located a corrugated strip 11, and outside of the corrugations is

placed concrete 12. Outside of the concrete is secured a casing 15 by the screws 16. The front 1 of the safe, and the supplemental back 7 are placed against opposite sides of the plastering 13 of the partition and the studding 14 serves to give a firm support to the safe. By this construction, the safe is supported within an opening in the partition 45 and cannot be taken down except by removing the fastening means through the door opening.

I claim as my invention.

1. A walled safe comprising a safe proper 50 having a flanged front, a supplemental back, and means connecting the supplemental back to the back of the safe proper, said means manipulated only through the door opening of the safe proper.

2. A walled safe comprising a safe proper, a supplemental back secured to the back of the safe proper, and a corrugated strip located exterior to the sides, back and ends of the safe proper.

3. A walled safe comprising a safe proper, a supplemental back secured to the back of the safe proper, a corrugated strip located exterior to the sides, back and ends of the safe proper and concrete embedding the corrugated strip.

In testimony whereof I have hereunto set my hand in presence of two subscribing witnesses.

EDWARD C. KELONGE.
